UNITED STATES PATENT OFFICE.

KENNETH J. UNWIN, OF SHREWSBURY, MASSACHUSETTS, ASSIGNOR TO CROMPTON & KNOWLES LOOM WORKS, OF WORCESTER, MASSACHUSETTS, A CORPORATION OF MASSACHUSETTS.

THREAD CUTTER FOR LOOMS.

Application filed April 18, 1927. Serial No. 184,624.

This invention relates to improvements in filling thread cutters for weft replenishing looms and it is the principal object of the invention to provide improved actuated means for the cutter to the end that the same may be caused to operate with the minimum number of parts.

Multi-color weft replenishing mechanisms of the type in common use employ a top shaft and a shuttle feeler, the top shaft being rocked just prior to transfer for the purpose of placing the transfer latch in the path of a bunter on the lay. Said top shaft is also attached by means of a connecting rod to the shuttle feeler to cause the latter to move into the path of the shuttle immediately prior to transfer, the purpose of this construction being to prevent transfer if the shuttle be improperly placed with respect to the magazine.

In co-pending application Ser. No. 127,695 filed by Chevrette there is shown a thread cutter mounted on a shuttle feeler and actuated by a rod the lower end of which is connected to the pivotal jaw of the cutter and the upper end of which is fast with respect to the magazine. Due to the varying shapes of different frames it is a matter of practical difficulty to provide a support or holder for the upper end of the cutter actuating rod which will be applicable to all styles of magazine looms. It is an important object of my present invention to provide means for attaching a cutter operating rod to the aforementioned connecting link between the top shaft of the magazine and the shuttle feeler. I find that this connecting link moves downwardly a short distance but this movement is not sufficient to interfere with the correct operation of the cutter.

In certain mountings for the upper end of the cutter rod provision is made for securing only one end of the holder for the rod so that there is a possibility that the holder may become loose. It is a further object of my invention to provide a holder for the cutter operating rod which shall be held at two spaced points so that it will always be in proper position and I achieve this result by employing the aforesaid connecting link as a support for the holder.

With these and other objects in view which will appear as the description proceeds, my invention resides in the combination and ar-

angement of parts hereinafter described and set forth in the claims.

In the accompanying drawings wherein I have shown one embodiment of my invention.

Fig. 1 is a view of the lower part of a weft replenishing mechanism of the multi-color type as viewed from the interior of the loom and showing my invention applied thereto with the cutter in non-operative position.

Fig. 2 is a detailed horizontal section on line 2—2 of Fig. 1.

Fig. 3 is an enlarged horizontal detailed section on line 3—3 of Fig. 1, and

Fig. 4 is a view similar to Fig. 1 but showing the cutter in operative position.

Referring to the drawings I have indicated a loom frame 10 to which is secured a weft replenishing mechanism 11 of the multi-color type. Said mechanism has mounted on the upper portion thereof a shaft 12 which is given an oscillation just prior to transfer by mechanism not shown but well understood to raise the transfer latch into the path of a bunter not shown but carried by the lay L.

A shuttle feeler carrier 13 is pivotally mounted on stud 14 fixed with respect to the replenishing mechanism and having an arm 15 which has pivotal connection as at 16 with the lower end of a connecting link 17 the upper end of which is connected to an arm 18 secured to the shaft 12. A second arm 19 of the carrier 13 has bolted thereto a shuttle feeler 20 having its lower edge curved as at 21 to be engaged either by the wall of the shuttle S or the box back B.

Under normal conditions the shuttle feeler carrier 13 is in the position shown in Fig. 1 with the connecting link 17 raised. Prior to the time of transfer the link 17 will be depressed by a slight oscillation of shaft 12 to move the shuttle feeler to the position shown in Fig. 4. If a shuttle be misplaced it will engage the under edge 21 of the shuttle feeler and restore the carrier and shaft 12 to normal position, thus preventing transfer. The matter thus far described is a common construction and may be the same as set forth in Patents Nos. 1,022,108 and 1,030,748.

The cutter unit is mounted on the shuttle feeler and comprises a cutter jaw 30 pivoted to said feeler as at 31 and having a cutter blade 32 which cooperates with a cut-

ting edge 33 ground on the shuttle feeler 20. Said cutter jaw 30 has pivotal connection as at 34 with the lower end of an extensible and adjustable operating rod 35. A clamp 36 5 may be secured to the shuttle feeler and have the lower portion thereof toward the selvage of the cloth offset as at 37, Fig. 2, to lie against the blade 32. The cutter may be substantially the same as set forth in the said co- 10 pending application Ser. No. 127,695 filed by Chevrette.

My invention relates more particularly to the means for supporting the upper end of the operating rod 35 and in carrying my 15 improvements into effect I provide a two part clamping holder indicated generally at 40 and having members 41 and 42 lying on opposite sides of the connecting link 17. Said members are provided with facing V- 20 shaped notches 43 and member 42 may be provided with a stud 44. Screws 45 may be employed for securing the two members together and clamping them tightly to the link 17 and the stud 44 has pivotal connection 25 with the upper end of the rod 35. When it is desired to vary the movement of the cutter jaw 30 the screws 45 may be loosened and the holder member 40 either raised or lowered along the link 17.

30 From the foregoing it will be seen that I have made use of the ordinary equipment of a multi-color weft replenishing mechanism to afford a support to the upper end of a cutter operating rod and that said rod is held at the lower end by the shuttle feeler and at the upper end by arm 18, so that there is no danger of the stud 44 changing its position in such a way as to interfere with the proper operation of the cutter. It will 35 further be seen that the holder 40 may be moved along the link 17 and that the operating rod 35 may be extended to the proper length to effect correct operation of the cutter. Also, it will be seen that vertical ad- 40 justment of holder 40 and adjustment of link 35 permit easy changing either of the stroke of the cutter or the movement of the shuttle feeler.

Having thus described my invention it will 45 be apparent that changes and modifications may be made therein by those skilled in the art without departing from the spirit and scope of the invention and I do not wish to be limited to the details herein disclosed, but what I claim is:

1. In a thread cutting mechanism for a weft replenishing loom having a shuttle feeler normally out of the path of the shuttle, a part to be moved prior to transfer and a link between said part and the shuttle feeler whereby the shuttle feeler is moved into the path of the shuttle prior to transfer by reason of said link, in combination, a filling thread cutter pivotally mounted on the shuttle feeler, and an operating rod connect-

ed to the cutter and said link and effective when the shuttle feeler is moved in the path of the shuttle to open the cutter and to close the cutter when the shuttle feeler is restored to normal position.

2. In a thread cutting mechanism for a weft replenishing loom having a shuttle feeler normally out of the path of the shuttle, a part to be moved prior to transfer and a link between said part and the shuttle feeler whereby the shuttle feeler is moved into the path of the shuttle prior to transfer by reason of said link, in combination, a thread cutter movably mounted on the shuttle feeler and normally closed, and an operating rigid connection between the aforesaid link and said cutter effective to open the cutter when the shuttle feeler is moved into the path of the shuttle and also effective to close the cutter when the shuttle feeler is restored to normal position.

3. In a thread cutting mechanism for a weft replenishing loom having a shuttle feeler normally out of the path of the shuttle, a part to be moved prior to transfer and a link between said part and the shuttle feeler whereby the shuttle feeler is moved into the path of the shuttle prior to transfer by reason of said link, in combination, a thread cutter mounted on the shuttle feeler for pivotal movement relatively thereto, an operating member attached to the thread cutter, and connections between the operating member and the aforesaid link, said operating member effective when the shuttle feeler is moved into the path of the shuttle to open said cutter and also effective when said shuttle feeler is restored to normal position to close the cutter.

4. In a thread cutting mechanism for a weft replenishing loom having a shuttle feeler normally out of the path of the shuttle, a part to be moved prior to transfer and a link between said part and the shuttle feeler whereby the shuttle feeler is moved into the path of the shuttle prior to transfer by reason of said link, in combination, a cutter pivotally mounted on the shuttle feeler, an adjustable device mounted on the link, and operating connections for the cutter interposed between the latter and the device on the link, said operating connections being effective when the shuttle feeler is moved into the path of the shuttle to open the cutter and effective also when the shuttle feeler is moved out of the path of the shuttle to close said cutter and give the same cutting movement.

5. In a thread cutting mechanism for a weft replenishing loom having a shuttle feeler normally out of the path of the shuttle, a part to be moved prior to transfer and a link between said part and the shuttle feeler whereby the shuttle feeler is moved into the path of the shuttle prior to transfer by

reason of said link, in combination, a thread cutter pivotally mounted on the shuttle feeler, a block removably and adjustably held to the aforesaid link, and an operating member 5 interposed between the block and the cutter, said operating member being effective when the shuttle feeler is moved to shuttle feeling

position to open the cutter and effective when the shuttle feeler is moved out of the shuttle feeling position to give the cutter a 10 cutting movement.

In testimony whereof I have hereunto affixed my signature.

KENNETH J. UNWIN.
